W. D. LA RUE

BOX OR RECEPTACLE FOR HOLDING SMALL ARTICLES

Filed July 11, 1921

WITNESS

F. J. Hartman.

BY Blount, Moulton & Helbert AT ATTORNEYS

INVENTOR

UNITED STATES PATENT OFFICE.

WILLIAM D. LA RUE, OF PHILADELPHIA, PENNSYLVANIA, ASSIGNOR TO VICTOR TALKING MACHINE COMPANY, A CORPORATION OF NEW JERSEY.

BOX OR RECEPTACLE FOR HOLDING SMALL ARTICLES.

Application filed July 11, 1921. Serial No. 483,723.

My invention relates to boxes which are adapted to hold relatively small articles such as styli or needles for talking machines, and more particularly to such boxes as are 5 provided with various compartments in certain of which may be stored or contained needles or styli suitable for use in the talking machine and in certain other of which may be dropped and stored styli which are 10 worn or for any reason are unsuitable for use in the machine.

The objects of my invention are to provide a box of the character above referred to, in which usable or unused styli may be 15 stored in one or more readily accessible compartments, preferably adjacent the front edge of the box, and the used, worn or discarded styli may be stored in a separate and distinctive compartment at the rear there- 20 of; to provide a box from which the accumulation of worn or discarded styli may be emptied from time to time without discharging or spilling out the new or usable styli or needles from their compartment or compart- 25 ments, by merely inverting the box as a whole; and to provide a simple structure which, when not in use, will not be unsightly, but on the contrary will present a pleasing and ornamental appearance.

30 A further object of my invention is to provide a box in which the tray containing one or more compartments for needles or styli or other small articles is tightly retained in position merely by the friction between the 35 end walls of the tray and the sides of the box, so that when it is necessary or desirable to remove the tray, it may be readily pulled bodily out of the box without disturbing the contents of the tray and without 40 being obliged to first remove any tray fastening or retaining means.

45 A further object of my invention is to provide a box with a hinged or pivoted member adapted to be swung at will to lie over and to cover the section or compartment containing used or worn needles, or over the compartment or compartments containing the unused or usable styli or needles.

50 Other objects of my invention will appear in the specification and claims below.

In the drawing forming a part of this specification and in which the same reference characters are used throughout the various views to designate the same parts, Fig. 1

is a perspective view of my improved box 55 with the hinged or swinging member lying over the compartment adapted to contain worn, unusable needles or styli, leaving open the entire tops of the compartments adapted to contain the new or usable needles or styli, 60 the contents thereof being readily accessible.

Fig. 2 is a perspective view of the box in- 65 verted for the purpose of discharging or pouring out the contents of the rear com- partment.

Fig. 3 is a transverse vertical section 65 through the device from front to rear.

Fig. 4 is a transverse vertical section taken on the line 4-4 in Fig. 3.

Fig. 5 is a vertical cross sectional view 70 similar to Fig. 3 but showing the cover in open position and the hinged or swinging member lying over and covering the tray and the compartments therein.

Fig. 6 is a fragmentary view of the rear 75 corner of the box and the free edge of the swinging member slightly elevated above it, showing the projections on the rear edge of the swinging member forming stops and adapted to rest on the top edges of the box, 80 and also showing a portion of the swinging member adapted to close an opening in the rear wall of the box where it is cut away for the purpose of forming a hinge for the cover.

85 In carrying out my invention I provide a box 1 preferably stamped or pressed out of sheet metal and having preferably a square or rectangular opening in the top thereof and having a pair of opposite side walls 2, 3 90 which are parallel at the top or opening into the box and are disposed perpendicular to the plane of the top of the box. The front and the rear walls 4 and 5 respectively, may be and preferably are also parallel to each 95 other at and around the top of the box, and are similarly preferably disposed in planes perpendicular to the opening of the box, but below the said perpendicular portions of the said walls 2, 3, 4 and 5 they may be 100 and preferably are flared outwardly and then reversely curved inwardly or into any desirable pleasing or attractive ornamental shape.

105 The top of the rear wall is preferably cut away to provide portions 6'-6" of the hinge 6. A cover 7 is also preferably provided along one edge thereof with a projection 6"

which also forms a part of the hinge 6, said portions or projection 6', 6', 6'' being bent or wrapped around the pintle 8 to form the hinge 6 by means of which the cover 7 is pivoted to one edge of the box 1.

Within the box is fitted a tray 9 located preferably adjacent the front wall 4 of the box. This tray is of such a length that when it is inserted into the box 1 its 10 ends press tightly against the opposite perpendicular parallel portions of the side walls 2, 3 of the box 1, and when the tray 9 is forced into the box it will be retained permanently in position by reason of the 15 friction between the side walls 2, 3 of the box and the ends of the tray 9.

In width this tray is preferably one-half of the width of the top of the box. The rear wall 10 of the tray therefore divides 20 the box as a whole into two sections, namely, a section forming a rear compartment 11 within the box and a front section provided by the tray 9 of the box. This tray 9 may be divided into two or more compartments 25 12, 12 as will be again referred to below.

The height of the tray 9 is preferably equal to the depth of the interior of the box 1, so that when the tray 9 is inserted into the 30 box it rests upon the bottom 13 of the box and its top edges are substantially flush with the top edges of the box.

Portions 14', 14' of the top edge of the rear wall 10 of the tray 9 are preferably 35 rounded over and around pintle 15 to form one part of the hinge 14, and to this hinge 14 is secured a hinged or swinging member 16, the same being substantially of the same size and shape as the top of the tray, and 40 since the top of the tray is of the same size and shape as the top of the rear compartment 11, the said swinging member 16 will be of the same size as the top of the rear compartment 11. This hinged or swinging member 16 is also provided with a projecting 45 portion 14'' which is also bent or wrapped around the pintle 15 to form a part or portion of the hinge 14. The hinged or swinging member 16 is thus adapted to be 50 swung into two positions. When it is swung rearwardly it will cover and close the rear compartment 11 of the box, and when it is swung forwardly it will lie over and close the entire top of the tray and the 55 compartments 12 therein.

The hinged or swinging member 16 is preferably provided at its free edge with a right-angled flange 17 of a size adapted to lie over and close that portion of the rear 60 wall 5 of the box which is cut away to form the hinge 6 when said swinging member 16 lies over and covers the rear compartment 11. The free edge of the swinging member 16 is also provided with 65 two small projections 18 at the opposite

ends thereof, adapted to rest on the top edges of the box when the said swinging member 16 is placed in either its forward or rear position. These projections 18 form stops which prevent the swinging member 70 16 from dropping below the plane of the top edges of the box.

The swinging member 16 is also preferably provided with a narrow elongated hole or opening 19 through which the worn, 75 used or discarded needles may be dropped into the rear compartment.

To assist in positioning the tray 9 within the box 1 a finger or lug 20 may be struck upwardly from the bottom 13 of the box and 80 against this finger 20 rests or bears the rear wall 10 of the tray 9. The tray may be provided with one or more vertical partitions 21 to divide the tray into as many compartments 12 as may be found to be desirable. Since the tray 9 is preferably adapted to contain the new, unworn, or usable needles or styli, different kinds of needles or styli may be stored or kept therein. Thus, "soft tone" needles may be kept in 90 one compartment 12 and "full tone" styli may be kept in a different separate compartment 12 in the tray 9.

The bottom of the tray 9 is preferably concavely curved upwardly toward the front 95 edge thereof so that the styli contained therein may be readily abstracted therefrom by means of the thumb and finger.

When using the device, the swinging member 16 is normally placed into the position 100 shown in Fig. 1 over the rear compartment 11 of the box, leaving the compartments 12, 12 in the tray open with the needles contained therein accessible for use.

When the accumulation of worn or discarded styli in the rear compartment is so great that it is desired to remove them from the box, it is only necessary to swing the hinged or swinging member 16 forwardly on its hinge 14 until it lies over and closes 110 the compartments 12, 12 in the tray. The thumb is then preferably placed over the hole 19 in the said swinging member 16, the box as a whole is then inverted and the contents of the rear compartment may 115 be thus emptied therefrom, but during this inversion of the box the styli in the tray 9 will be retained in their respective compartments 12 by the swinging member 16. The inverted position of the box and the 120 way in which it is held when emptying styli from the rear compartment is clearly illustrated in Fig. 2.

In order that the swinging member 16 may lie in a plane substantially flush with 125 the top of the box when it is swung to its rear position over the compartment 11, the rear wall 5 of the box may be provided with slight recesses 22 upon which the stops or projections 18 rest. When the swinging 130

member 16 is swung to a forward position the said projections 18 rest on the front edge of the tray 9.

The free edge of the swinging member 16 is also preferably provided with a projection 23, preferably a little wider than the projections or stops 18 and preferably also disposed in the plane of the major portion of the swinging member 16 and preferably 10 located at or about the middle thereof, to provide a finger hold which may be caught under the finger nail to facilitate the lifting of the swinging member 16 from either of its positions, over the rear compartment 15 11 or over the tray compartments 12.

If for any reason it is desirable to remove the tray 9 it may be pulled directly out of the box without being obliged to first remove any fastening or securing 20 means therefor. The tray is of a size to fit snugly and tightly within the box. It is so securely held there that no other means than the frictional engagement between the ends of the tray and the side walls of the 25 box is necessary to firmly hold it permanently within the box. The finger or lug 20 is primarily a positioning means to assist in uniformly locating the tray 9 within the box and to prevent the tray from being 30 moved away from the side of the box, but it may assist or contribute in frictionally retaining the tray within the box by reason of the frictional engagement between the rear wall 10 of the tray and the lug or 35 projection 20.

The bottom of the box may be provided with projections 24 forming legs, preferably stamped or pressed outwardly from the material forming the bottom of the box.

40 While I have shown and described only one embodiment of my invention in which the box is substantially rectangular and the compartment for worn and discarded styli is at the rear thereof adjacent the hinged 45 cover, it is to be understood that the mouth or opening into the box or container may be of any suitable shape and that the tray may be positioned adjacent one of the sides of the box.

50 The tray may be made as one entire compartment or it may be sub-divided into any convenient number of compartments adapted to contain a number of different kinds of unused needles but in any case the size and 55 shape of the top of the tray should be the

same as that of the other or discarded needle compartment, or the rear wall 10 of the tray 9 should divide the entire mouth or opening into the box into two equal similarly shaped parts so that when the swinging 60 member 16 is swung to either of its positions it will completely close, except as to the hole 19 therein, either half of the box, that is to say, it will close either the compartment or section 11 or the entire top of 65 the tray.

Having thus described my invention, I claim and desire to protect by Letters Patent of the United States:

1. A container for small articles comprising a box, a removable tray retained within said box by the friction between the ends thereof and the walls of said box, means to definitely position said tray within said box and to assist in holding it from sliding 70 within said box, a wall of said tray dividing the opening into said box into two equal parts, and a swinging member hinged to the top edge of said wall of said tray and adapted to be swung to cover either part of 75 said opening.

2. A container for small articles comprising a box, one wall of which is cut away to provide a hinge, a tray within said box, a wall of said tray dividing the opening 85 into said box into two parts, a swinging member hinged to the top edge of said wall of said tray and adapted to be swung at will to cover either part of said opening, said swinging member being provided with 90 a flange adapted to fit over and close said cut-away portion of said wall.

3. A container for small articles comprising a box one wall of which is cut away to provide a hinge, a tray within said box, 95 a wall of said tray dividing the opening into said box into two equal parts, a swinging member hinged to the top edge of said wall of said tray and adapted to be swung at will to cover either part of said opening 100 said swinging member being provided with a flange adapted to fit over and close said cut-away portion of said wall, and a stop on said swinging member to hold said member in the plane of the edges of said 105 opening into said box.

In witness whereof, I have hereunto set my hand this 8th day of July, A. D. 1921.

WILLIAM D. LA RUE.
